CRUTCH PAD

Clarence M. Fallon, San Diego, Calif., assignor of
one-half to Minnie Louise Fallon, San Diego,
Calif.

Application April 23, 1935, Serial No. 17,812

10 Claims. (Cl. 135—52)

This invention relates to an improved pad or cushion construction which is mounted upon the upper end portion of a crutch to protect the arms of crutch users adjacent to the arm pits.

5 The present application pertains to an improvement upon the crutch pad described and claimed in my Patent No. 1,980,044, issued November 6, 1934. Insofar as the comfort of the user is concerned, the merits of the present invention are similar to those set forth in the patent above referred to, but the present invention embodies additional advantages among which are lowered cost of manufacture and more convenient replacement of the pneumatic sac whenever 10 this becomes necessary on account of wear or injury.

The invention is not limited to the use of a pneumatic pad, but includes also a novel crutch structure whereon a non-pneumatic pad may be 20 supported in an improved manner.

Other objects, advantages and features of invention may hereinafter appear.

Referring to the accompanying drawing, which illustrates what is at present deemed to be preferred embodiments of the invention:

Fig. 1 is a perspective view of the complete structure.

Fig. 2 is a transverse sectional detail taken on line 2—2 of Fig. 1.

30 Fig. 3 is a vertical section on line 3—3 of Fig. 1.

Fig. 4 is a vertical section on line 4—4 of Fig. 1.

Fig. 5 is a perspective view of a modification parts being broken away to contract the view and other parts being broken away to uncover interior 35 structures.

Referring in detail to the drawing, the crutch member 5 is bifurcated to provide the usual two staff arms 6 which are held in properly spaced relation to each other not only by the lower spacing pin 7 but also by the cross bar 8 near the upper end of the crutch.

The upper end portion of each staff arm 6 is cut away or deeply notched for more than half its breadth, thus providing a shoulder 9 at each side 45 of the crutch substantially on a level with the upper surface of the cross bar 8, said shoulders both being located near the same side of said bar. In the assembled structure the end portions of the pneumatic rubber bag or short tube 10 are seated 50 in the two angular notches resulting from cutting away the structure above the shoulders 9, in the manner above stated, leaving the narrow upper staff arm extensions 11.

In order to secure said tube 10 in place and at 55 the same time provide an efficient closure means

for its end portions, the clamping pieces or followers 12 are furnished, said pieces having thru each of them a plurality of bolt holes 13. The oppositely disposed staff parts 11 are likewise provided with alining bolt holes, in order that 5 bolts 14 may be inserted and nuts 15 screwed on to them to afford a clamping means. Preferably the parts 11 and 12 are respectively countersunk at 16 and 17, and washers 18 may also be used. The end portions of the tube 10 will, of course, be 10 perforated where the bolts pass thru them.

As an additional means for securing an air tight closure of the end portions of the tubular member 10 a short cord 20 is extended longitudinally across the inner face of each staff part 11 near 15 the bolt holes therethru, thus producing a line of additional pressure transversely of the ends of the tube 10 to close the ends thereof in an air tight manner when the nuts 15 have been screwed down. 20

The pad 10 is provided with a conventional inflating tube or stem 21 which is led down thru a hole 22 provided therefor thru the cross bar 8.

In Fig. 5 is shown a modification which differs from the form already described only in that reinforcing metal strips 25 are inserted in grooves provided for them in the upper face of the cross bar 8a near each end thereof, said strips 25 having their outer end portions fitted within notches 26 cut into the shoulders 9. Thru each end of said 30 strip and the side walls of the notch 26 at that side extends a bolt 27, and bolts 28 thru the grooved portions of the cross piece 8a and the strips 25 complete the structure. 35

It should be understood that the present disclosure is for the purpose of illustration only and that this invention includes all modifications and equivalents which fall within the scope of the appended claims. 40

I claim:

1. A crutch structure including a pneumatic tube positioned to form a pad for the arms of the user, and means to mount said tube upon the crutch and to clamp its end portions to close them in an air tight manner. 45

2. A crutch structure including a pneumatic tube positioned to form a pad for the arms of the user, a crutch staff portion overlying one side of said tube near each end thereof, and clamping means including followers which engage the opposite side of said tube to grip the end portions thereof and close them air tight. 50

3. A crutch structure including a pneumatic tube positioned to form a pad for the arms of the user, a crutch staff portion extending across 55

one side of said tube near each end thereof, clamping pieces which oppose said staff portions, cords extending across said tube between said pieces and the opposed staff portions, and clamping elements to force said staff portions and said pieces towards each other and then maintain them in the clamping condition.

4. A crutch structure including a pneumatic tube positioned to form a pad for the arms of the user, a crutch staff portion extending across one side of said tube near each end thereof, clamping pieces which oppose said staff portions, cords extending across said tube between said pieces and the opposed staff portions, and bolts 10 provided with nuts to complete the clamping structure.

5. In a crutch structure, a staff having separated arms at its upper end, a pad positioned to protect the arms of the user, said pad bridging the space between said staff arms, and clamping means mounted on each of said staff arms and gripping the end portions of said pad.

6. In a crutch structure, a staff having separated arms at its upper end, a pad positioned to protect the arms of the user, said pad bridging the space between said staff arms, a cross bar which unites said arms and underlies said pad to aid in supporting it, and clamping means mounted on each of said staff arms and gripping the end 25 portions of said pad.

7. In a crutch structure, a staff having separated arms at its upper end, a pad positioned to protect the arms of the user, said pad bridging the space between said staff arms, a clamping member mounted on each of said staff arms and gripping the end portions of said pad, and a cord 30 interposed between at least one of said clamping members and the adjacent side of said pad to produce a line of additional pressure across said pad.

8. In a crutch structure, a staff having separated arms at its upper end, a pad positioned to protect the arms of the user, said pad bridging the

space between said staff arms, a cross-bar which unites said arms below said pad, and a reinforcing strip for an end portion of said cross bar, there being recesses in said cross-bar and the adjacent staff arm to receive said strip, and securing 5 means to keep said strip in place.

9. In a crutch structure, a staff having separated arms at its upper end, a cross-bar bridging the space between said arms, said cross-bar being near the upper end of said staff, the ends of said cross-bar abutting against the inner sides of said arms, there being grooves in the upper sides of the end portions of said cross-bar which open out at the ends thereof, reinforcing strips occupying said grooves and having end portions which 10 project beyond the ends of said cross-bar, there being recesses in said arms into which the projecting end portions of said strips extend, means to secure said projecting end portions of said strips to said arms and to secure the remaining 15 portions of said strips to said cross-bar, and a pad mounted upon the crutch above said cross-bar.

10. In a crutch structure, a staff having separated arms at its upper end, a cross-bar bridging 25 the space between said arms, said cross-bar being near the upper end of said staff, the ends of said cross-bar abutting against the inner sides of said arms, there being grooves in the upper sides of the end portions of said cross-bar which open 30 out at the ends thereof, reinforcing strips occupying said grooves and having end portions which project beyond the ends of said cross-bar, thereby providing shoulders near the end of said cross-bar, grooves extending across said shoulders into 35 which the projecting end portions of said strips extend, means to secure said strips severally in the two grooves thus provided therefor, a pad mounted above said cross-bar and having end portions occupying the spaces above said shoulders, and clamping means above said shoulders engaging the end portions of said pad.

CLARENCE M. FALLON.
